[57] CLAIM

The ornamental design for a carpet sweeper, as shown and described.

DESCRIPTION

FIG. 1 is a perspective view of a carpet sweeper showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational thereof, the opposite side being a mirror image;

FIG. 7 is a perspective view of a second embodiment thereof;

FIG. 8 is a front elevational view thereof;

FIG. 9 is a top plan view thereof; and,

FIG. 10 is a side elevational view thereof, the opposite side being a mirror image.

The bottom and rear view of the second embodiment is the same as FIGS. 3 and 5.

FIG. 1

FIG. 6

FIG. 2

FIG. 4

FIG. 3**FIG. 5**

FIG. 7

FIG. 10

FIG. 8

FIG. 9
